United States Patent Office

Des. 229,549

Patented Dec. 11, 1973

229,549

CASSETTE DISPLAY PACKAGE OR THE LIKE

Joseph A. Mascetti, Jr., Geneva, Ill., assignor to Plastofilm Industries, Inc., Wheaton, Ill.

Filed Feb. 1, 1972, Ser. No. 222,712

Term of patent 14 years

Int. Cl. D9—03

U.S. Cl. D9—182

FIG. 1 is a front plan view of a cassette display package or the like showing my new design;

FIG. 2 is a right side view thereof;

FIG. 3 is a back plan view thereof;

FIG. 4 is a top view thereof;

FIG. 5 is a bottom view thereof, and

FIG. 6 is a cross-sectional view taken at the line 6-6 of FIG. 3.

I claim:

The ornamental design for a cassette display package or the like, substantially as shown.
